Primary Examiner — Kevin Rudzinski(74) *Attorney, Agent, or Firm* — Cheng-Ju Chiang(57) **CLAIM**

The ornamental design for a power part of electronic cigarette, as shown and described.

DESCRIPTION

FIG. 1 is a top, front and right perspective view of a power part of an electronic cigarette showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, front and right side perspective view of the power part and a mouthpiece part of an electronic cigarette released away; and,

FIG. 9 is a top, front and right side perspective view of the power part and the mouthpiece part of the electronic cigarette assembled together.

The broken line illustration of the mouthpiece part of the electronic cigarette in FIGS. 8 and 9 forms no part of the claimed design.
